(57) **CLAIM**

The ornamental design for a drawing tool as shown and described.

DESCRIPTION

FIG. 1 is a front isometric view of a drawing tool showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines in FIGS. 1 and 6 of the drawings illustrate numerical text and the broken lines in FIG. 7 illustrate circular elements on a bottom surface. The broken lines form no part of the claimed design.
